ENGINE INTAKE REGULATING MEANS

Thorpe Hiscock, Seattle, Wash., assignor, by
mesne assignments, to United Air Lines Transport
Corporation, a corporation of Delaware

Application November 2, 1933, Serial No. 696,350

4 Claims. (Cl. 123—119)

This invention relates to internal combustion engines and more particularly to the regulation of the fuel mixture supplied to such engines, especially such as airplane engines which are subjected to substantial changes in atmospheric pressure.

One of the objects of my invention is to control the pressure in the carburetor intake.

Another object of my invention is to control the air density in the engine intake.

Still another object of my invention is to automatically maintain constant pressure at a predetermined maximum value in the carburetor intake.

Further and other objects and advantages will be apparent from the specification and claims and from the accompanying drawing which illustrates what is now considered the preferred embodiment.

The figure shows a diagrammatical view of my carburetor intake pressure and temperature regulator.

Variations in atmospheric pressure and in temperature have long been known to affect the action of the carburetor of an internal combustion engine. In order to have the carburetor of an engine which is required to operate under these varying atmospheric conditions perform satisfactorily, it is provided with means for changing the quantity of liquid fuel supply, thereby changing the fuel-air ratio. Such means are called mixture controls and are operated manually to secure the desired engine performance.

According to the present invention, means are provided to automatically maintain the pressure and temperature of the air conducted to the carburetor intake substantially constant at predetermined values. By thus regulating the pressure and temperature of the carburetor intake air, the fuel air ratio is, with a properly designed carburetor, automatically maintained constant.

By limiting the predetermined maximum pressure in the carburetor intake, the maximum power output and the maximum combustion chamber pressure are limited to a predetermined safe maximum. This becomes of special value when the engine is operating in an atmospheric pressure which, unless controlled, would produce such a high pressure in the carburetor intake that excessive pressures would be developed in the engine.

The invention disclosed in the present application is shown as applied to a conventional radial airplane motor 16 with a supercharger

blower 12 driven from engine crankshaft 8 by gears 6 and taking fuel mixture from the carburetor 14 through conduit 16 and delivering it to diffuser 18 and thence through conduits 20 to the various engine cylinders.

Air is supplied to the carburetor through a conduit 22 having branches 24 and 26 for leading hot and cold air respectively thereto. A valve 28 is placed at the junction of conduits 24 and 26 and is pivoted so that it may regulate the ratio of hot to cold air admitted to conduit 22 and thereby regulate the resultant temperature of the air in that conduit.

A valve 30 is placed in conduit 22 and is adapted to restrict the free area of that conduit and thereby regulate the pressure in that conduit especially between the valve and the carburetor while the engine is operating and air is being conducted through the conduit.

A pressure regulating device, indicated generally at 32, is provided to operate the valve 30. The pressure regulating device may be any device capable of giving a large resultant movement for a small change in pressure. In the modification shown, this pressure regulator comprises an evacuated metallic bellows 34, usually balanced against collapse by means of a spring, not shown, placed inside the bellows. This bellows is placed to act directly against a similar bellows 36 connected with the conduit 22 between valve 30 and the carburetor. These two bellows act on a lever 38 to operate pistons 40 and 42 which control the admission of oil under pressure to opposite sides of the piston 44. Oil under pressure, usually from the engine lubricating system, is led into conduits 46 and 48, and the pipe 50 conducts oil back to the engine sump or other storage tank.

Bellows 34 and 36 acting against each other balance out any change in external pressure so that the pressure regulator is unaffected by any change in atmospheric pressure such as that due to altitude. Any change of pressure in conduit 22 operates bellows 36 and in turn the servo mechanism to operate valve 30 and return the pressure to the predetermined value.

In order to automatically maintain a constant fuel air ratio, it is necessary to automatically maintain a constant density in the carburetor intake. Although the pressure remains constant, variation in the temperature of the intake air will affect the fuel-air ratio supplied by the carburetor.

In the embodiment shown, I have provided means to regulate this temperature so that to

gether with the pressure regulation, a substantially constant air density may be maintained. I have shown a temperature regulator represented generally at 52 in which a metallic bellows 54 actuates a servo mechanism similar to that described for the pressure regulator and which it is considered unnecessary to again describe in detail. The bellows 54 is connected with temperature responsive element 56 so that 10 temperature changes operate the bellows and in turn the servo mechanism which, in turn, operates the valve 28 to control the proportions of cold and hot air admitted to the carburetor intake. Differences in atmospheric pressure would 15 affect the action of the bellows 54 and in order to overcome the effect of altitude changes on this bellows, it is encased in an air-tight housing which is vented to the constant pressure area of the conduit 22. By this means, a constant 20 pressure is maintained on the bellows 54 so that the temperature regulation is independent of atmospheric pressure.

It is to be noted that the temperature and 25 pressure in conduit 22 are regulated by the temperature and pressure in that conduit independent of any external conditions. Hence, when the mechanism is set for any predetermined pressure and temperature, that pressure and temperature is automatically maintained in 30 dependent of changes of external pressure or temperature, engine speed or any other external condition within the limits for which the mechanism is designed.

While this device finds particular use in connection with the regulation of the air intake 35 of a carburetor, it may also find other uses, such as the regulation of the pressure, temperature, or density of the air intake of a fuel injection engine or other engines on which a similar regulation is of value.

While I have explained this invention in connection with what is now thought to be the preferred form of mechanism, it is to be expressly understood that other mechanisms may be used 45 and various modifications may be made. It is, therefore, to be expressly understood that my invention is not limited to the specific mechanism shown, but may be used in various other ways without departure from its spirit as shown 50 by the following claims.

What I claim is:

1. In combination with an internal combustion engine, a carburetor therefor, and an air intake for said carburetor, means for maintaining the air flowing through said carburetor to said engine constant at a predetermined density, said means comprising, means in said intake for regulating the pressure of the air in said intake, means responsive to changes in the pressure of the air in said intake for controlling said regulating means to maintain said pressure constant at a predetermined value, means in said in-

take for regulating the temperature of the air flowing therethrough, and means responsive to the temperature and pressure of the air in said intake for controlling said temperature regulating means to maintain the temperature of said air constant at a temperature corresponding to the pressure in said intake to provide a constant air density.

2. In combination with an internal combustion engine, a carburetor therefor, and an air intake for said carburetor, means for maintaining the air flowing through said carburetor to said engine constant at a predetermined density said means comprising, means in said intake ahead of said carburetor for regulating the pressure of the air in said intake, means responsive to changes in the pressure of the air in said intake for controlling said regulating means to maintain said pressure constant at a predetermined value, means in said intake ahead of said pressure regulating means for regulating the temperature of the air flowing through said intake, and means responsive to the temperature and pressure of the air between said pressure regulating means and said carburetor for controlling said temperature regulating means to maintain the temperature of said air constant at a temperature corresponding to the pressure in said intake to provide a constant air density.

3. In combination with an internal combustion engine, a carburetor therefor and an intake for said carburetor, means for maintaining the air flowing through said carburetor to said engine constant at a predetermined density, said means comprising, means in said intake ahead of said carburetor for regulating the pressure of the air in said intake, means responsive to changes in the pressure of the air in said intake for controlling said regulating means, means in said intake ahead of said pressure regulating means for regulating the temperature of the air flowing through said intake, and means comprising an expandible element surrounded by air of the pressure of the air in said intake between said carburetor and said pressure regulating means responsive to the temperature of the air in said intake for controlling said temperature regulating means to maintain the temperature of said air constant at a temperature corresponding to the pressure in said intake to provide a constant air density.

4. In an internal combustion engine, in combination, an air intake, and means for regulating the density of the air in said intake to maintain constant a predetermined air density, said means comprising, means responsive to the pressure of the air in said intake for controlling said pressure, and means responsive to the temperature of the air at said controlled pressure for controlling the temperature of the air in said intake.

THORP HISCOCK.
